DEVICE FOR MAKING BUTTER CURLS
OR BUTTER ROLLS

Ted Bauman, Milwaukee, Wis.

Application June 23, 1944, Serial No. 541,719

2 Claims. (Cl. 31—7)

My invention relates to improvements in devices for making buttercurls or butterrolls. More specifically, my invention relates to a new and improved device of the character described which is designed for individual serving in restaurants, hotels, and households.

The main object of the present invention is the provision of a device of the character described which will facilitate the making of buttercurls or rolls and which will enable anybody to make attractive and easy-to-spread buttercurls or rolls without touching the same by human hands.

Another object of the present invention is the provision of a device of the character described which will prevent the butter from sticking to any parts of the device with which butter may come in contact.

A further object of the present invention is the provision of a device of the character described which is comparatively small in size and light in weight so that it can be placed on the table and which reduces the time necessary for making buttercurls or rolls to a minimum; thus each person can produce his own buttercurls or rolls for immediate use, and it will no longer be necessary to prepare a certain quantity of curls which, when not used immediately, are more subject to deterioration than butter which is kept in the form of a cake.

Still a further object of the present invention is the provision of a device of the character described which is simple in construction, inexpensive to manufacture, but sturdy and well adapted to the rough usage to which such devices are usually subjected.

Further objects of the instant invention reside in any novel feature of construction or operation or novel combination of parts present in the embodiment of the invention described and shown in the accompanying drawing whether within or without the scope of the appended claims and irrespective of other specific statements as to the scope of the invention contained herein.

In the drawing:

Figure 1 is a top plan view of a preferred embodiment of my invention.

Figure 2 is a section view on the line 2—2 of Figure 1.

Figure 3 is a front elevation; and

Figure 4 is a side elevation of the device.

Similar numerals refer to similar parts throughout the several views.

A U-shaped plate 1 having side panels 2 and being carried by a standard 3 forms the base por-

tion of the device. U-shaped guides 4 are rectangularly secured to plate 1 by means of angle and U-irons 5 or in any other suitable manner. A floorboard 6, of a material which prevents butter from sticking thereon, is carried by the plate 1. I prefer to make the floorboard 6 of hard wood and to wet it with water before the cake of butter, which is indicated by dash-and-dotted lines in Figures 2 and 4, and to which the numeral 7 denotes, is placed thereupon.

The cutter 8 is slidable in and detachable from the guides 4 and is adapted to form one, two, or more curls of butter at each downward stroke.

I prefer to carry out this feature of my invention in the manner shown in the drawing, where it will be seen that the corrugated cutting edge 9 is angularly disposed to the cake of butter 7, and that it is subdivided by one or more small blades 10 (one in the present instance),

20 which is arranged at right angles to cutting edge 9. A piece 11 (Figures 2 and 4) of a material which prevents butter from sticking thereon is secured to the lower side of the cutter 8 and is provided with two longitudinal grooves 12 and 14 at its lower side. These grooves 12 and 14 are curved in such a manner that groove 12, which is adjacent to the cutting edge 9, causes the butter slide 15 to curl (Figure 2), and that groove 14 serves as a guide as the curl 16 becomes larger (Figure 4).

25 The parts 17, which are secured to the cutter 8 or to the piece 11 as in the instance shown, engage the U-shaped guides 4, which are open at the top so that the cutter unit consisting of the parts 8, 9, and 11 can be pulled out over the top of the guides 4. I prefer to make the piece 11 of hard wood and to dip the cutter unit—

particularly the piece 11—before operating the device, first in hot and then in cold water; hot water soaks quickly into the hard wood piece 11, and the cold water causes closing of the pores of the hard wood so that the piece 11 will remain wet during a considerable period of time during which the device may be in use. The corrugation of the cutting edge 9 will produce attractive

45 easy-to-spread rolls or curls and the blade 10 will subdivide the curl into two buttercurls, so that two buttercurls will be produced during each downward stroke of the cutter 8. Instead of one blade 10 there can also be arranged two or more blades 10 in order to produce three, four, or more small buttercurls during each downward stroke. A handle 18 is extended from the cutter 8 so that it will not be necessary to touch directly any parts of the cutting unit during the operation 50 of the device.

In order to cause the butter curls cut off from the cake 7 to fall from the cutting edge 8 at the completion of the downward stroke, I prefer to provide the lower end of the guides 4 with stop bolts 18 which are supported by springs 49 (Figures 2, 3, 4) to allow the cutter 8 to move rapidly downward so that a slight shock will be created at the completion of the downward stroke. This shock will cause the curl to fall from the metal cutting edge 8 on which it otherwise might adhere thus preventing the buttercurls or rolls from being touched by human hands.

Whereas the cutter construction and arrangement previously referred to is one feature of my invention, a further feature of my invention consists in means for automatically and gradually moving the cake 7 of butter toward the cutter while the same is being reciprocated.

For this purpose, I prefer to provide the cutter unit with rollers 20 laterally extending therefrom and being adapted to engage curved levers 21 which are pivotally secured to the outer sides of the guides 4 at 22. The upper portion 23 of each lever 21 is bent or curved outwardly as may be seen in Figure 4, whereas the lower end of each lever 21 is provided with a protruding portion 24. Thus the levers 21 will be moved in an anti-clockwise direction at the completion of the upward stroke of cutter 8, and they will be moved around pivot 22 in a clockwise direction at the completion of the downward stroke when the rollers 20 engage the protruding portions 24.

A vertical back panel 25, having a horizontal portion 27 from which panels 28 protrude laterally, is arranged in such a manner that it can press against the rear portion of the cake of butter 7. The panels 28 are extended through slots 29 in the side panels 2 (Figures 2 and 4). Ratchet bars 30, which engage the panels 28, are pivoted to the lower portions of the levers 21 at 31. I prefer to connect the ratchet bars 30 to each other by means of a crosspiece 32, which may form a unit with the ratchet bars 30 and which has a handle 33 so that the ratchet bars 30 can be disengaged conveniently from the panels 28. The tilting movement imparted to the levers 21 by the rollers 20, when the cutter 8 is reciprocated, causes a forward and backward movement of the ratchet bars 30, and this movement of the ratchet bars 30, which engage the panels 28, causes a gradual movement of the back panel 25 and of the cake 7 toward the cutter 8.

Thus the cake 7 of butter, once it has been placed upon the floorboard 6 has no longer to be touched by human hands and the curls cut off from the cake 7 at each downward stroke of cutter 8 will be of equal thickness.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

Having thus described my invention, what I claim and desire to secure by Letters Patent in the United States is:

1. A device for making butter curls comprising a horizontal base adapted to carry a cake of butter, vertical guides secured to said base, a corrugated cutter adapted to be reciprocated along said guides, a panel adapted to push said cake toward said cutter, ratchet bars adapted to engage pawls extending from said panel, a curved lever pivotally connected to each of said ratchet bars and tiltably secured to one of said guides, and rollers carried by said cutter being adapted to engage said curved levers.
2. A device for making buttercurls comprising a corrugated cutter which is detachable from and vertically slidable in two guides and the cutting edge of which is angularly disposed to a cake of butter, a blade being rectangularly arranged to the cutting edge of said cutter and being adapted to subdivide the buttercurl cut off from said cake by the cutter, a piece of material which prevents butter from sticking thereon being secured to the lower side of said cutter and having two longitudinal grooves at its lower side, a base carrying said guides, a floorboard of a material which prevents butter from sticking thereon being secured to the upper side of said base, a panel adapted to push said cake toward said cutter, ratchet bars adapted to engage pawls extending from said panel, a curved lever pivotally connected to each of said ratchet bars and tiltably secured to one of said guides, and rollers carried by said cutter being adapted to engage said curved levers.

TED BAUMAN.
